ICE-CREAM CONE VENDING MACHINE

Hughes Heinig, Detroit, Mich.

Application November 15, 1951, Serial No. 256,577

12 Claims. (Cl. 312—96)

1

This invention relates to an ice cream cone vending machine, and more particularly to a coin controlled ice cream cone vending device.

It is the object of the present invention to provide a very simplified coin machine which employs a minimum of moving parts and which is fully effective for its intended purpose.

It is the further object of this invention to provide in a vending machine mechanism for delivering ice cream cones selectively in different flavors.

It is the further object of this invention to provide a novel control mechanism for regulating the delivery of ice cream cones upon insertion of the necessary coin within the proper slot.

It is the further object of this invention to provide a simplified cone vending device which is durable and sturdy and compact in its arrangement of parts.

These and other objects will be seen from the following specification and claims in conjunction with the appended drawings in which:

Fig. 1 is a front elevational view of the ice cream cone vending machine.

Fig. 2 is a side elevational view thereof partially broken away and sectioned for illustration.

Fig. 3 is an elevational section thereof illustrating the arrangement of the cone supporting sprocket chains, and mounting mechanisms and the control for rotation thereof.

Fig. 4 is a fragmentary section taken on line 4—4 of Fig. 3.

Fig. 4a is a section taken on line 4a—4a of Fig. 4.

Fig. 5 is an enlarged plan view of the upper chain and sprocket supporting circular plate shown in Fig. 3, being a section taken on line 5—5 of Fig. 3.

Fig. 6 is a bottom plan view of the circular control plate being a section on line 6—6 of Fig. 3.

Fig. 7 is a diagrammatic plan view of a vending machine showing the preferred arrangement of a series of chain and sprocket supporting plates whereby the vending machine may dispense different flavors of ice cream cones.

Fig. 8 is a diagrammatic view of the wiring in conjunction with the coin controlled switch for a particular chain supporting sprocket wheel.

Fig. 9 is a wiring diagram illustrating the connections between certain switches and a control mechanism for regulating the rotative positioning of the sprocket wheel supporting discs.

Fig. 10 is an elevational section similar to Fig. 3 illustrating a slightly different vending device which eliminates all electrical controls.

2

Fig. 11 is a fragmentary section taken on line 11—11 of Fig. 10.

Fig. 12 is a fragmentary section taken on line 12—12 of Fig. 11; and

Fig. 13 is a bottom plan view of the control disc for regulating the rotary positioning of the sprocket and chain supporting plates shown in Fig. 10, being a section taken on line 13—13 of Fig. 10.

It will be understood that the above drawings illustrate merely certain preferred embodiments of the invention and that other embodiments are contemplated within the scope of the claims hereinafter set out.

Referring to the drawings, Figures 1 through 9 illustrate one embodiment of the present cone vending machine employing certain electrical controls; whereas Figs. 10 through 13 illustrate a similar device, which is entirely mechanical and which eliminates the electrical controls.

Referring to Figs. 1 and 2, the ice cream vending machine includes an upright hollow housing 11 having a bottom wall portion 12 upon which is supported a conventional electrical refrigerating mechanism 13 adapted to supply refrigerant throughout the coil 14 to suitable refrigerating plates upon the interior of housing 11 and its upper housing element 17.

The refrigerating mechanism 13—14 forms no part of the present invention and, therefore, further description thereof is omitted. Naturally, it is contemplated for a device of this type that the housing be sufficiently refrigerated upon the interior thereof so as to maintain the preassembled ice cream cones in a frozen condition until dispensed. Thus, the vending machine should be insulated upon its interior, such as by the insulation generally indicated at 11', which insulation is only fragmentarily shown in Fig. 3 of the drawings.

Removable cover 15 is positioned within a rectangular opening in the front wall of housing 11, there being suitable means provided for retaining said cover in position; and said cover has a pair of handles 16 to facilitate its removal when desired to permit access to the lower interior portion of housing 11.

Housing 11 has upon its upper portion the upper housing member 17 which encloses the various mechanisms for storing and delivering pre-assembled ice cream cones of the desired flavor.

The present apparatus is constructed for dispensing as many as four different flavors if desired, however, the following description will be directed to one of the storage and control mech-

anisms for dispensing ice cream cones of one flavor.

The housing portion 17 is provided with a suitable coin slot 18 which is associated with a suitable coin control mechanism for closing the electrical switch 17 shown in Fig. 3 for operation in the manner hereafter described.

The particular coin control mechanism is a standard device which may be purchased on the open market and its mechanism forms no part of the present invention and consequently its description and illustration is omitted. The important function of the coin control mechanism is to close the electrical switch 17 upon the insertion of a proper coin within the coin slot 18 shown in Fig. 1.

There is also provided a coin return chute 19, which is associated with the coin control mechanism in a conventional manner, and which itself forms no part of the present invention.

Upon the front wall of housing 11-17 there is formed a horizontal ledge 30 and a series of cone delivery openings, normally closed by the manually liftable doors 20.

Said doors, as shown in Fig. 3 are guided upon their opposed upright edges by the guideways 28, and may be manually lifted by the outwardly projecting handles 21.

There are provided coil springs 29 anchored at their upper ends upon the interior of the front wall of housing 17, with their lower ends bearing upon the top edge of the door 20 normally urging the door to a closed position. While said springs are not essential, the same materially assist the automatic dropping and closing of the door 20, when the handle 21 is released.

There are provided within the front wall of housing 17, a series of windows 22 through which the desired flavor of ice cream cone may be ascertained. There is also provided a door 23 which is hinged at 24 at its side upon the front wall of housing 17. Said door may be opened by the handle 21. It is contemplated that a suitable lock 25 may be employed, if desired, for the door 23.

As shown in Fig. 3, an elevated platform 31 is provided within the housing 11 and secured to the side walls thereof, which platform has a transverse circular opening through which extends the lower end of the rotatable upright shaft 32. The lower end of said shaft is supported and journalled within the thrust bearing 33 secured to the undersurface of the platform 31, such as by the bolts 34.

The upper end of shaft 32 is rotatably journaled and supported within the bearing member 35 secured to the interior top wall surface of housing 17 as by the bolts 36.

Discs or supporting plates 37 and 39 are secured adjacent opposite ends of the shaft 32 by means of a suitable key 38 as shown in Figs. 3 and 5.

Both of the plates 37 and 39 are circular in shape and are adapted to support a plurality of sets of upright radially arranged chain supporting sprocket wheels 45 and 56 in the manner hereafter described.

Both of the plates 37 and 39 are provided with a plurality of radially arranged slots 40 which terminate at their inner ends in the enlarged circular openings 41, as shown in Fig. 5. Fig. 5 pertains to the upper plate 39. Positioned within each of the radial slots 40 is a sprocket wheel 45 with its respective central outwardly directed stud shafts 44 journalled within the bracket ele-

ments 42 arranged upon opposite sides of each slot and secured to plate 39 as by the bolts 43.

The lower circular plate 37 is constructed the same as the plate 39 and is adapted to support and rotatably journal thereon the plurality of sprocket wheels 56, whose oppositely directed stud shafts 57 are similarly journalled within suitable brackets 58 secured upon plate 37 in the same manner as above described with respect to brackets 42.

A sprocket chain 46 extends around and interconnects each corresponding vertically aligned pair of sprocket wheels 45 and 56. In the present embodiment there are shown eight sprocket chains 46 in Fig. 5 respectively interconnecting eight pairs of vertically aligned sprocket wheels. It will be noted that some of these sprocket chains have been omitted from Fig. 3 for purpose of clarity of illustration.

Each of the sprocket wheels 45 have formed therein adjacent their outer periphery, a pair of transverse slots 47 and 48 which are preferably arranged at 180 degrees from each other. The slots 47 and 48 are adapted to alternately receive therein the spring loaded plunger pin 49 of the solenoid 50 which is mounted upon plate 39 adjacent slot 40 and secured to said plate as by the bolts 51. It will be seen from Fig. 5 that there is a separate solenoid provided for each sprocket wheel 45.

In operation it will be seen that the solenoid pin 49 will normally retain the sprocket chain 46 stationary by locking the sprocket wheel 45 against rotation.

In the manner hereafter described, the insertion of a suitable coin within the appropriate coin slot 18 will operate a coin controlled mechanism for momentarily closing the electrical switch 17 completing the electrical circuit to solenoid 50. This will momentarily withdraw the pin 49 against the action of a spring within the solenoid 50 and permit the sprocket wheel 45 to rotate 180 degrees by virtue of the weight 54 secured to chain 46 as at 55, until said pin 49 moves into the second slot 48 in sprocket wheel 45 under the action of the spring within solenoid 50.

Each of the sprocket chains 46 has secured thereto, in vertically spaced relation and upon one side of said chain, a plurality of ice cream cone holders or pins 52. Pins 52 are secured to the chains 46 as by the hinges 53 which will permit upward tilting only of said pins from a horizontal position. The weight 54, as shown in Fig. 3 is secured at the upper end of the outer portion of sprocket chain 46 and is constantly urging said chain downwardly.

The downward movement of said chain is thus controlled by the pin 49 of solenoid 50 and the two transverse openings 47 and 48 formed in each of the sprocket wheels 45.

When the machine is loaded there will be, in the embodiment shown in Fig. 3, eight ice cream cones 59-60 respectively mounted and hung upon the cone supporting pins 52.

When the particular sprocket chain 46, directly facing the particular door 20 is initially loaded, the lowermost cone will be in the position indicated by the letter A. Upon a suitable coin effecting a closing of the switch 17 against contact 30, Fig. 3, the solenoid 50 will be momentarily energized to withdraw pin 49 from transverse opening 47 in sprocket wheel 45. The chain 46 will move downwardly due to the weight of the cones as well as the additional weight 54, until

pin 49 registers with and automatically seats within opening 68 of sprocket wheel 45.

This will place the above described lowermost ice cream cone A in the position B directly in front of the door 20; and said cone may be 5 manually removed from the dispensing device merely by lifting the door 20.

Directly in front of the door 20 upon the interior of housing 11 there is provided an arcuate chute 62 which extends inwardly of platform 30 and which has an upturned wall. It will be noted from Figs. 3 and 4 that the chute 62 is arranged directly in the path of downward movement of the ice cream cone 59—60, and is so constructed that the pin 52 as it moves downwardly engages the said chute and may be tipped upwardly to further assure disengagement of pin 52 from an opening in cone wrapper 61. As the chain 46 moves downwardly the chute 62 engages the undersurface of cone 59 and removes the same from the downwardly moving pin 52.

As above described and from Figs. 3 and 5, it is apparent that once all the cones 59—60 have been removed from the sprocket chain 46 nearest the door 20, the next set of cones on an adjacent sprocket chain may be presented to the door 20 by rotation of shaft 32. There must be such rotation of plates 37, 39 as will position the next conveyor chain opposite from the particular door 20.

In the manner hereafter described, a suitable spring urged cable is provided for effecting a rotation of shaft 32. It is necessary, however, that the rotation of said shaft and the plates 37 and 39 be accurately controlled so that the rotation can be stopped at the correct instant, i. e. when the necessary conveyor chain is directly in front of the particular door 20.

For this purpose a circular, preferably non-metallic disc 63 is keyed as at 64 to the shaft 32 below plate 37, and preferably above the platform 31.

The disc 63 has formed transversely therethrough adjacent its outer periphery a plurality of circularly spaced slots 65 which are so arranged that each slot is directly under and lying in a plane with a corresponding sprocket chain 46.

A plurality of circularly spaced contacts 66 are also arranged upon the undersurface of the disc 63 spaced inwardly from the slots 65, with each said contacts 66 arranged on a radial line corresponding to one slot 65.

Each of the contacts 66 is separately connected electrically to the electrically conductive shaft 32 by the conductors 67 shown in Figs. 6 and 9.

A suitable electric solenoid 69 is secured to platform 31 directly below the circle of openings 65 of plate 63 so that the plunger pin 68 of said solenoid will be normally urged by its contained spring into one of the slots 65 in plate 63 to retain the same against rotation.

A contact switch 70 is also provided upon the platform 31 and joined to solenoid 69 by the conductor 71. Said switch as illustrated in Figs. 3 and 9, includes a spring urged contact pin 73 adapted for intermittent engagement with the contacts 66 which are flush with the bottom surface of disc 63.

A suitable drum 72 is keyed as at 73 to shaft 32, preferably below the plate 63, and has wound thereon several turns of a cable or rope 74, which cable is suitably anchored at one end to said drum 72.

The opposite end of the cable 74 is joined to a coiled spring 75 which is anchored as at 76 to the

platform 31. The spring is of such strength as to effect a rotation of drum 72 and shaft 32 secured thereon whenever the solenoid pin 68 has been withdrawn from a disc opening 65.

Referring to Fig. 8 there is shown a wiring diagram, which is adapted to control one of the solenoids 50 for controlling the particular sprocket wheel 45 carrying the chain 46 which is arranged at the moment directly in front of the door 20.

The coin controlled mechanism above referred to, is adapted to intermittently close the electric switch 77 with respect to the contact 80 on the lead wire 81 which connects one of the solenoids 50. The switch 77 is joined by the lead 78 to a power line 79. Similarly, the other side of solenoid 50 is joined by a wire 81 to the ground or second power line 82 to thus complete the electric circuit to solenoid 50 whenever the coin controlled switch 77 is momentarily closed.

While only one electrical circuit is shown in Fig. 8, it is obvious that there must be a similar separate electrical circuit for each of the solenoids 50 shown in Fig. 5; however, the coin controlled switch 77 in each of said circuits will be closed by the coin controlled mechanism only when the particular solenoid is arranged directly in front of the door 20.

Referring to the Figs. 3 and 9, a contactor 86 30 is secured to and projects from the upper end of conveyor 46 and is adapted to engage the movable arm 85 on limit switch 84 to close the electrical circuit from power line 79, through electrical leads 83 to the solenoid 69. As shown in 35 Fig. 9 there is provided an additional lead 71 to the switch 70 which has a contact arm 88 movably projected therefrom urged outwardly by the coiled spring 87. The arm 88 is adapted for engagement with the contact 66, also shown in 40 Fig. 6. The lead 67 connects contact 66 with the electrically conductive shaft 32, the latter being joined to power line 82 by the lead wire 89.

The purpose of this contact 66 is to assure that the solenoid 69 will be momentarily energized sufficiently to permit the withdrawal of the plunger or pin 68, which is spring loaded. This momentarily releases the control disc 63 so that the shaft 32 will rotate due to the torque produced by the spring loaded cable 74 shown in Fig. 3.

It will be noted from Fig. 6 that upon slight 50 rotary movement of the disc 63, contact 66 will be disengaged from the switch plunger 88 to thereby de-energize solenoid 69. This means that the solenoid plunger 68 will ride along the undersurface of the electrically non-conductive disc 63 until said plunger registers with the next opening 65 in disc 63. At this moment the plunger under the action of its spring will move into the opening 65 and retain the disc 63 against further movement.

It is contemplated that the lead 71, switch 70, plunger 88 and the contacts 66 could be eliminated, as well as the lead 67. In this case, the lead wire 89 would be directly joined to the solenoid 69. This means that the limit switch 84 would be used to momentarily energize solenoid 69 as the element 86 moved past limit switch arm 85.

The above described pre-assembled ice cream cone 59—60 is preferably covered with a suitable wrapping 61, and this wrapping as shown in Fig. 3, has a transverse opening at its upper end to receive the outer end of the cone supporting pin 52 on conveyor 46.

In operation as the lowermost cone engages

the upper end of the chute 62, the cone wrapping 61 will be disengaged from the pin 52 as the conveyor moves downwardly.

Fig. 7 is a diagrammatic illustration showing the present cone vending machine as having in addition to the sets of upright radially spaced conveyors 46, additional sets of conveyors 90, 91, and 92, identical to the sets above described. Thus, different flavors of cones may be dispensed from the machine, with each series of conveyors dispensing a single flavor of ice cream.

In loading the conveyors of a particular series, the serviceman who stocks the machine will load one conveyor by manually releasing the plunger 49 from sprocket wheel 45 to allow the conveyor and cone supporting pins to be brought into position. After all the cones are mounted upon one conveyor he will release the plunger pin 68 and revolve the plates 37 and 38 until the disc 63 locks in its next position. He will repeat this procedure until the entire set of conveyors is loaded. The action of rotating the plates 37 and 38 will be pulling against the spring 75 and will be winding the cable 74 upon the drum 72 placing the shaft 32 under the tension of the spring 75. Thus when the pin 68 is intermittently disengaged from the disc 63, the shaft 32 will automatically rotate under the action of said cable and spring.

The embodiment of the invention shown in Figs. 10 through 13 is slightly different from the machine above described in that the electrical controls are eliminated and mechanical devices are employed which control the downward movements of each conveyor selectively and which also control the spaced rotary movements of the conveyor supporting shaft.

The construction of the housing, the chute, and the conveyor mounting is exactly the same as above described with respect to Fig. 3 of the drawing and, therefore, will not be repeated.

The only differences reside in the use of the U-shaped clips 52' which are hingedly mounted in vertically spaced relation at points 53' upon the conveyors 46.

Instead of the weight 54, there is shown in Fig. 10 a weight 54', which has a depending shaft 93 adapted for operatively engaging the disc control pin 95. Said pin is supported within housing 97 and normally urged upwardly by the spring 98. Said pin is adapted to restrainingly engage the sprockets 96 which are radially spaced around control disc 94. It is apparent that a momentary downward movement of pin 95 under the action of shaft 93 will release the control disc 94 and permit its automatic rotation under the action of the spring loaded cable 74.

Just as soon as the disc 94 and the conveyors begin to rotate, the pin 95 will be disengaged from the shaft 93 and will be repositioned in order to stop the rotary movement of the control disc 94 by engaging the adjacent sprocket 96 as shown in Fig. 13.

The manually and inwardly movable control arm 99 has a conventional coin receiving opening 100 and is slidably supported for reciprocal movement upon the horizontal guides 101 as shown in Fig. 11.

Arm 99 carries an actuating element 102 hinged thereon at 103. The member 102 is adapted for operative engagement with the arm 103 of rotatable sprocket 104 for rotating said sprocket 90 degrees past the leaf spring 105.

The sprocket 104 carries at its lower end a plurality of radially spaced clip supporting vanes

106 which thereby support the cone carrying clips 52' for controlling the downward movements of the particular conveyor 46.

It is apparent from Figs. 11 and 12, that the inward movement of the member 99 will rotate the sprocket 104 ninety degrees and temporarily disengage the cone supporting clip 52' permitting the conveyor to move downwardly. The next succeeding clip 52' directly above the preceding clip will rest upon the next succeeding vane 106. Thus, there is provided a manual control for regulating the intermittent downward spaced movements of the conveyors 46.

Referring to Fig. 1 of the drawing, there are shown four pushbuttons 26 whereby the proper flavor of ice cream cone may be selected. It is contemplated that there will be only one coin controlled mechanism within the housing adapted to operate the particular solenoid operating switch 77. Consequently, it is necessary to operate one of the pushbuttons 26 in order to tie-in the coin control mechanism with the desired series of conveyors of a pre-determined flavor of cone to be dispensed.

The diagram in Fig. 8 of the drawing shows the connection of one of the solenoids 50, shown in Fig. 5, with the adjacent sprocket wheel 45. Naturally, it is contemplated that the coin control mechanism will energize only the solenoid 50 which is adjacent the conveyor directly in front of a particular door 20. The other solenoids 50 remain inactive.

It is contemplated that each of the series of conveyors 90, 91, and 92 will have their own electrical circuits similar to that shown in Fig. 8 for controlling the particular solenoid of a particular series. The particular series will be selected by operating one of the pushbuttons 26 before or at the time that the necessary coin is inserted within coin slot 18. The pushbuttons will be associated with an electrical switch to thereby bring into play the particular electrical circuit, Fig. 8, for the particular series.

Having described my invention, reference should now be had to the claims which follow for determining the scope thereof.

I claim:

1. An ice cream cone vending machine comprising a hollow upright housing having a front wall, an upright conveyor movably mounted and supported therein, a plurality of vertically spaced cone supports upon said conveyor, a hook on the end of each support adapted to retain a cone thereon, an upright chute within said housing with its upper end adjacent the lower end of said conveyor and restrainingly cooperable with a cone thereon for disengaging the cone from the hook of its support as the conveyor moves downwardly, the lower end of said chute terminating in the front wall of said housing, a weight upon said conveyor above said cone supports normally urging said conveyor downwardly, and a solenoid with a spring biased plunger restrainingly engaging said conveyor and intermittently disengagable therewith upon energization of said solenoid permitting limited downward movements thereof.

2. An ice cream cone vending machine comprising a hollow upright housing having a front wall, a pair of upright vertically aligned transversely apertured sprocket wheels journaled within said housing, a continuous upright conveyor mounted upon said wheels, a plurality of vertically spaced cone supports upon said conveyor, an upright chute within said housing with its upper end adjacent the lower end of said con-

veyor and cooperable with a cone thereon for disengaging the cone from its support as the conveyor moves downwardly, the lower end of said chute terminating in the front wall of said housing, a weight upon said conveyor above said cone supports normally urging said conveyor downwardly, and a solenoid with a spring biased plunger retainingly engaging one of said sprocket wheels within an aperture thereof and intermittently disengageable therewith permitting limited downward movements of said conveyor.

3. An ice cream cone vending machine comprising a hollow upright housing having a front wall, a pair of upright vertically aligned transversely apertured sprocket wheels journaled within said housing, a continuous upright conveyor mounted upon said wheels, a plurality of vertically spaced cone supports upon said conveyor, an upright chute within said housing with its upper end adjacent the lower end of said conveyor and cooperable with a cone thereon for disengaging the cone from its support as the conveyor moves downwardly, the lower end of said chute terminating in the front wall of said housing, and a solenoid with a spring biased plunger retainingly engaging one of said wheels within an aperture thereof and intermittently disengageable therewith permitting intermittent limited downward movements of said conveyor.

4. An ice cream cone vending machine comprising a hollow upright housing having a front wall, a pair of upright vertically aligned sprocket wheels journaled within said housing, a continuous upright conveyor mounted upon said wheels, a plurality of vertically spaced cone supports upon said conveyor, an upright chute within said housing with its upper end adjacent the lower end of said conveyor and cooperable with a cone thereon for disengaging the cone from its support as the conveyor moves downwardly, the lower end of said chute terminating in the front wall of said housing, and a solenoid adjacent one of said wheels and having a spring urged plunger retainingly engaging said wheel, said solenoid upon intermittent energization effecting an intermittent disengagement of its plunger with said wheel permitting intermittent limited downward movements of said conveyor.

5. An ice cream cone vending machine comprising a hollow upright housing having a front well, a plurality of upright radially spaced conveyors movably mounted and supported therein, a plurality of vertically spaced cone supports upon each conveyor, an upright chute within said housing with its upper end adjacent the lower end of one of said conveyors and cooperable with a cone thereon for disengaging the cone from its support as said one conveyor moves downwardly, the lower end of said chute terminating in the front wall of said housing, and movable means retainingly engaging each of said conveyors, and intermittently operable control means connectable with the movable means engaging the conveyor adjacent said chute for effecting intermittent disengaging movement of said movable means permitting limited downward movement of said conveyors.

6. An ice cream cone vending machine comprising a hollow upright housing having a front wall, a plurality of upright radially spaced conveyors movably mounted and supported therein, a plurality of vertically spaced cone supports upon each conveyor, an upright chute within said housing with its upper end adjacent the lower

end of one of said conveyors and cooperable with a cone thereon for disengaging the cone from its support as said one conveyor moves downwardly, the lower end of said chute terminating in the front wall of said housing, movable means retainingly engaging each of said conveyors, intermittently operable control means connectable with the movable means engaging the conveyor adjacent said chute for effecting intermittent disengaging movement of said movable means permitting limited downward movement of said latter conveyor, support means within said housing upon which conveyors are mounted, and a torque effecting device joined to said supporting means for producing limited rotary movement of said support means for presenting an adjacent conveyor to said chute.

7. An ice cream cone vending machine comprising a hollow upright housing having a front wall, an upright rotatable shaft journaled within said housing, a pair of vertically spaced horizontal discs secured to said shaft, a plurality of upright vertically aligned pairs of upright sprocket wheels journaled upon said discs, with said pairs of wheels in radially spaced relation around said discs, a continuous upright conveyor movably mounted upon each pair of wheels, a plurality of vertically spaced cone supports upon each conveyor, a chute within said housing with its upper end adjacent the lower end of one of said conveyors and cooperable with a cone thereon for disengaging the cone from its support as the conveyor moves downwardly, the lower end of said chute terminating in the front wall of said housing, and a weight upon each of said conveyors above said cone supports normally urging said conveyors downwardly.

8. An ice cream cone vending machine comprising a hollow upright housing having a front wall, an upright rotatable shaft journaled within said housing, a pair of vertically spaced horizontal discs secured to said shaft, a plurality of upright vertically aligned pairs of upright sprocket wheels journaled upon said discs, with said pairs of wheels in radially spaced relation around said discs, a continuous upright conveyor movably mounted upon each pair of wheels, a plurality of vertically spaced cone supports upon each conveyor, a chute within said housing with its upper end adjacent the lower end of one of said conveyors and cooperable with a cone thereon for disengaging the cone from its support as the conveyor moves downwardly, the lower end of said chute terminating in the front wall of said housing, a weight upon each of said conveyors above said cone supports normally urging said conveyors downwardly, and movable means retainingly engaging one of said sprocket wheels selectively and intermittently disengageable with one of said wheels permitting intermittent limited downward movements of one of said conveyors.

9. An ice cream cone vending machine comprising a hollow upright housing having a front wall, an upright rotatable shaft journaled within said housing, a pair of vertically spaced horizontal discs secured to said shaft, a plurality of upright vertically aligned pairs of upright sprocket wheels journaled upon said discs, with said pairs of wheels in radially spaced relation around said discs, a continuous upright conveyor movably mounted upon each pair of wheels, a plurality of vertically spaced cone supports upon each conveyor, a chute within said housing with

its upper end adjacent the lower end of one of said conveyors and cooperable with a cone thereon for disengaging the cone from its support as the conveyor moves downwardly, the lower end of said chute terminating in the front wall of said housing, a weight upon each of said conveyors above said cone supports normally urging said conveyors downwardly, movable means retainingly engaging one of said sprocket wheels of each pair of sprocket wheels selectively and intermittently disengageable with one of said wheels permitting intermittent limited downward movements of one of said conveyors, and a torque source joined to said shaft for effecting intermittent rotary movements thereof to successively and intermittently present said conveyors to said chute.

10. An ice cream cone vending machine comprising a hollow upright housing having a front wall, an upright rotatable shaft journalled within said housing, a pair of vertically spaced horizontal discs secured to said shaft, a plurality of upright vertically aligned pairs of upright sprocket wheels journalled upon said discs, with said pairs of wheels in radially spaced relation around said discs, a continuous upright conveyor movably mounted upon each pair of wheels, a plurality of vertically spaced cone supports upon each conveyor, a chute within said housing with its upper end adjacent the lower end of one of said conveyors and cooperable with a cone thereon for disengaging the cone from its support as the conveyor moves downwardly, the lower end of said chute terminating in the front wall of said housing, a weight upon each of said conveyors above said cone supports normally urging said conveyors downwardly, movable means retainingly engaging one of said sprocket wheels of each pair of sprocket wheels selectively and intermittently disengageable with one of said wheels permitting intermittent limited downward movements of one of said conveyors, a drum secured on said shaft, and a spring loaded cable secured to and wound around said drum for effecting intermittent rotary movements thereof to successively and intermittently present said conveyors to said chute.

11. An ice cream cone vending machine comprising a hollow upright housing having a front wall, an upright rotatable shaft journalled within said housing, a pair of vertically spaced horizontal discs secured to said shaft, a plurality of upright vertically aligned pairs of upright sprocket wheels journalled upon said discs, with said pairs of wheels in radially spaced relation around said discs, a continuous upright conveyor movably mounted upon each pair of wheels, a plurality of vertically spaced cone supports upon each conveyor, a chute within said housing with its upper end adjacent the lower end of one of said conveyors and cooperable with a cone thereon for disengaging the cone from its support as the conveyor moves downwardly, the lower end of said chute terminating in the front wall of said housing, a weight upon each of said conveyors above said cone supports normally urging said conveyors downwardly, movable means retainingly engaging one of said sprocket wheels of each pair of sprocket wheels selectively and intermittently disengageable with one of said

wheels permitting intermittent limited downward movements of one of said conveyors, a drum secured on said shaft, a spring loaded cable secured to and wound around said drum for effecting intermittent rotary movements thereof to successively and intermittently present said conveyors to said chute, a control disc secured to said shaft, and movable means retainingly engageable with said disc and intermittently disengageable therewith to permit intermittent spaced rotary movements of said shaft.

12. An ice cream cone vending machine comprising a hollow upright housing having a front wall, an upright rotatable shaft journalled within said housing, a pair of vertically spaced horizontal discs secured to said shaft, a plurality of upright vertically aligned pairs of upright sprocket wheels journalled upon said discs, with said pairs of wheels in radially spaced relation around said discs, a continuous upright conveyor movably mounted upon each pair of wheels, a plurality of vertically spaced cone supports upon each conveyor, a chute within said housing with its upper end adjacent the lower end of one of said conveyors and cooperable with a cone thereon for disengaging the cone from its support as the conveyor moves downwardly, the lower end of said chute terminating in the front wall of said housing, a weight upon each of said conveyors above said cone supports normally urging said conveyors downwardly, movable means retainingly engaging one of said sprocket wheels of each pair of sprocket wheels selectively and intermittently disengageable with one of said wheels permitting intermittent limited downward movements of one of said conveyors, a drum secured on said shaft, a spring loaded cable secured to and wound around said drum for effecting intermittent rotary movements thereof to successively and intermittently present said conveyors to said chute, a control disc secured to said shaft, movable means retainingly engageable with said disc and intermittently disengageable therewith to permit intermittent spaced rotary movements of said shaft, and a control member upon each of said conveyors operatively engageable with said movable means upon a predetermined downward movement of said conveyor.
